TOOL FOR INSTALLING CONDUIT CLIPS

Eugene M. Morehouse, Tujunga, Calif., assignor to
 Adel Precision Products Corp., a corporation of
 California

Application September 20, 1943, Serial No. 503,123

3 Claims. (Cl. 81—3)

1

This invention relates to a tool by means of which conduit supporting clips may be installed in air craft, and embodies as hereinafter pointed out certain improvements in the tool shown in my United States Letters Patent No. 2,359,237, issued September 26, 1944, and entitled "Installation tool for conduit clips."

The primary object of the present invention is to provide a tool of the character described which may be readily applied and operated in many different angles and positions on either side of a conduit clip instead of in the manner to which the tool of said application is limited, will afford easier access to the apertured ends of the clip in inserting a screw or bolt therethrough and in installing or removing the screw or bolt; requires a smaller amount of movement of the operating lever, is much more rugged and dependable in operation, and saves time, labor and installation costs compared to tools as heretofore provided.

A further object of my invention is to provide a tool of the character described in which the jaws for gripping and holding the apertured ends of the clips in alignment are substantially coplanar when in position to hold said ends together, instead of being in different planes with the outer jaw well below the plane of the inner jaw as in my former tool, thereby making it possible to apply the tool with the lever on the lower or upper side of the tool and with the tool in different positions and angles on either side of the clip, and assuring the bringing of the apertures in the ends of the clip into registration, also disposing the tool so that it does not interfere with straight or angular insertion of the bolt or screw into said apertures, since in all positions of the tool the inner jaw and adjacent parts are spaced to one side of said apertures a greater distance than in my former tool where in case of misalignment of the apertures and an angular insertion of the bolt is necessary, the inner jaw often prevents or renders difficult such an angular insertion of the bolt.

Another and more specific object is to provide a tool of the character described in which the arm or link member connecting the inner and slidably jaw with the operating lever is constructed to afford easy access to the apertures in the ends of the clip in placing or removing the bolt or screw in said apertures and in manipulating a screw driver to set up or remove the bolt or screw.

With the foregoing objects in view, together with such other objects and advantages as may

2

subsequently appear, the invention resides in the parts and in the combination, construction and arrangement of parts hereinafter described and claimed, and illustrated by way of example in the accompanying drawings, in which:

Fig. 1 is a top plan view of a tool embodying my invention as when being brought into position to engage the conduit clip mounted on a conduit;

Fig. 2 is a side elevation of the tool as when in the position shown in Fig. 1;

Fig. 3 is an elevational view showing an end of the tool as when the outer jaws are engaged with the outer face of one of the ends of the clip;

Fig. 4 is a fragmentary top plan view of the tool showing the outer jaws lying between the structural member on which the clip is supported and said clip, preliminary to removing the tool;

Fig. 5 is a fragmentary top plan similar to Fig. 4 showing the manner of spreading and releasing the jaws from their Fig. 4 position after the clip is secured in place;

Fig. 6 is a bottom plan view of the tool when folded into collapsed position;

Fig. 7 is a side elevation partly in section showing one way of applying and operating the tool;

Fig. 8 is an elevational view with the tool applied in a reverse manner to its Fig. 7 position;

Fig. 9 is an elevational view showing the tool applied from the opposite side of the clip compared to Figs. 7 and 8; Fig. 10 is a fragmentary side elevational view, partly in section, showing a preferred manner of applying the tool when the adjacent structures permit, whereby the tool is disposed in out-of-way position relative to the aligned apertures and the operator may insert a screw and screw driver for quickly and easily securing the clip in place without having the tool interfere with such installation.

Referring to the drawings more specifically, it is seen that one embodiment of my improved tool includes a pair of opposed and preferably resilient metal arms 1 spaced apart in substantial parallelism so that certain corresponding in-

wardly turned and somewhat pointed ends thereof will constitute a pair of opposed outer jaws 2 adapted to lie against the outer face of either of the apertured ends 3 and 4 of a resilient metal conduit-embracing band-like strap 5 depending on which of said apertured ends said jaws are positioned in the use of the tool, while said arms extend across and opposite to the side edges of the ends 3 and 4.

The strap 5 forms the body portion of a standard conduit supporting clip now well known in

the art and supports a conduit-embracing cushion 6. The ends 3 and 4 of the strap are wide and flat and normally spaced apart as shown in Figs. 1 and 2 and must be brought together with their apertures aligned as shown in Figs. 4 and 10, for example, in order that a bolt or screw 7 may be inserted and manipulated to secure the clip on the conduit 8 as well as to a supporting structure 9.

The other or inner ends of the arms 1 are joined by a straight cross portion 10 which by means of a staple member 11 is pivoted to a lever 12 at a point approximately centrally of the ends of the lever as shown in Figs. 2 and 6.

In addition to providing the outer jaws 2 on their outer ends, the arms 1 slidably support a sliding jaw 13 extending transversely between said arms and which as here shown is one square end of a plate-like link or arm 14 pivoted at its other and reduced end as at 15 to the lever 12 at a point between one end of the lever and the portion 10 and nearer to said one end than to said portion 10. The sliding connection between the jaw 13 and the arms 1 is provided by means of two integral guide members 16 located at the ends of the jaw 13 which forms part of the plate-like link 14 and slidably hooked onto said arms as best shown in Figs. 3 and 6. The members 16 are formed as curled tongues bent to hook around the upper, outer and under sides of the arms 1. The plate-like character of the link 14 makes it possible to form said tongues at minimum cost.

The jaw 13 is adapted to engage the outer face of one of the apertured ends of the strap 5. For example, as shown in Fig. 2, if the jaws 2 are set against the outer face of the apertured end 3, then jaw 13 will engage the outer face of the other end 4 upon manipulating the lever 12 from position shown in Fig. 2 to position shown in Fig. 7, thereby clamping the ends 3 and 4 together as shown in Figs. 4 and 7, in preparation for applying the screw or bolt 7. The tool will remain in position shown in Fig. 7 due to its toggle action and past center movement of the lever 12 thereby leaving both hands of the operator free to install the nut or bolt.

The arms 1 are adapted to be spread apart to spread the jaws 2 apart whereby they may be readily moved into position to engage one of the ends 3 and 4 of the strap 5, after which the arms 1 and jaws 2 are moved toward one another to engage said one of said ends, for example as shown in Fig. 3. However, where the clip installation, the width of the ends of the clip, the construction of the support for the clip and adjacent structures permit, the jaws 2 and 13 may be positioned to engage the ends 3 and 4 of the clip without spreading the arms 1 and jaws 2 apart, it being only necessary to have the jaw 13 moved rearwardly along the arms 1 from jaws 2 sufficiently to bring the jaws downward over the ends 3 and 4 in opposition to the outer faces of said ends.

To provide for the spreading apart of the jaws 2, the arms 1 at points intermediate their ends have oblique and inwardly convergent portions 17 which when the guide members 16 and jaw 13 are moved thereon toward the inner or pivoted ends of the arms 1, will allow the arms 1 to spring apart, said arms being tensioned as to move apart as the jaw is moved in the manner above noted.

When the arms 1 are spread apart as shown in Figs. 1 and 5, the straight portions 18 of said arms extending between the jaws 2 and the convergent portions 17 will extend divergently from said portions 17. Therefore when the jaw 13 is moved

outwardly toward the jaws 2, the guide members 16 in sliding along the arm portions 18 will move portions 18 together thereby moving the jaws 2 into position to engage an end of the strap while the jaw 13 is moved to engage the other end of the strap. When the two ends 3 and 4 of the strap 5 are moved together, as shown in Fig. 4, the arm portions 18 are substantially parallel and substantially coplanar with the jaws 2 and 13.

It should be noted that the jaw 13 is notched as at 13' to accommodate the rib formations 3' and 4' on the strap ends 3 and 4 respectively whereby a close gripping contact of the jaw transversely of said ends is assured and the jaws are prevented from slipping out of place. Fig. 3 shows how the opposed jaws 2 lie on opposite sides of the rib 3' in a depression 5' formed by off-setting the end 3 relative to the strap 5. This makes the jaws 2 lie substantially flush with the outer face of the offset portion of the end 3 (see Figs. 3 and 4) and permits of withdrawing the jaws 2 by spreading them apart after the clip is installed, as shown in Fig. 4.

With the arms 1 substantially horizontally disposed as shown for example in Fig. 2, it is seen the arm portions 18 are downwardly inclined from and angularly related to the convergent portions 17 from the inner ends of which latter the remaining portions 19 of said arms leading to the pivot or cross portion 10 are extended angularly upward in the opposite manner to the portions 18. The link or arm 14 is bent or bowed outwardly intermediate its ends as at 20 so that the link is somewhat angular. These constructions and arrangements, together with the locations of the two pivots, make it possible to fully operate the tool with a lever movement of approximately 90 degrees of arc as against approximately 180 degrees of lever movement required in the tool shown in my former application and this saves time and effort and makes possible operation of the tool in confined spaces. Moreover, the various bends of the arms 1 and 14 provide for a straight line thrust of the jaws, the collapse of the tool into smaller compass than in the tool shown in said pending application, and make possible the application of the tool in the various positions shown in Figs. 7, 8, 9 and 10.

An important feature of this invention is that 50 of having the jaws 2 and 13 substantially coplanar instead of the jaws 2 being spaced well below the plane of jaw 13 as provided in the tool shown in said application. The straight portions 18 of the arms on which the jaw 13 rests when engaged 55 with one of the ends 3 and 4 make this possible, it being noted that in my former tool the portions of the arms corresponding to portions 18 hereof were arcuate.

By having the jaws 2 and 13 coplanar or substantially so, it is seen they will more effectively grip and hold the ends 3 and 4 of the strap and pull them together so as to insure alignment of the apertures therein. Moreover, this arrangement of the jaws 2 and 13 makes it possible to apply the tool in the various ways shown in Figs. 7 to 10 inclusive.

Fig. 7 shows the jaws 2 and 13 engaging the ends 3 and 4 respectively with the tool nearly horizontal and the lever 12 uppermost. Fig. 8 shows the tool reversed and the lever lowermost. Fig. 9 shows the tool applied to bring jaws 2 against end 4 and jaw 13 against end 3. Fig. 10 shows the tool in the reversed position of Fig. 8, 75 and engaging the clip as shown in Fig. 7, but

the tool extends upwardly and obliquely outward as shown in Fig. 10.

To provide for ready access to the apertured ends 3 and 4 of the clip when the tool is set to hold said ends together, particularly as shown in Fig. 10, a large square opening 21 is provided in the arm or link 14. As shown in Fig. 10, the opening 21 fully exposes the ends 3 and 4 permitting of an easy insertion or removal of the bolt as well as the manipulation of a screw driver to set or remove the bolt even when the bolt must be angularly inserted or removed in case of misalignment of the apertures in said ends of the clip.

While I have shown and described specific embodiments of my invention I do not limit myself to the exact details of construction set forth, and the invention embraces such changes, modifications and equivalents of the parts and their formation and arrangement as come within the purview of the appended claims.

I claim:

1. In a tool for installing a band-like conduit-embracing and supporting clip having a pair of opposed ends adapted to be forced together to clamp the clip on a conduit and position said ends for application thereto of means for securing them together, a pair of opposed arms spaced apart and adapted to be positioned opposite corresponding edges of said ends of the clip, jaw means extending between said arms at certain corresponding ends thereof for engaging the outer face of one of the ends of the clip, an operating lever, means pivotally connecting the other ends of said arms to said lever to afford a fulcrum therefor, a slidable jaw supported on said arms for movement into and out of engagement with the outer face of the other of the ends of said clip, the portions of said arms on which said slidable jaw is positioned being straight, said jaw means and said slidable jaw being substantially coplanar when the latter is on said straight portions of said arms; and a connecting arm fixed at one end to said slidable jaw and pivoted at its other end to said lever at a point nearer to one end of the lever than to the fulcrum of the lever for sliding said slidable jaw on said pair of arms toward and away from said jaw means when said lever is rocked on its fulcrum, said connecting arm having an opening therein adjacent said sliding jaw to permit of access to the ends of the

clip therethrough when the tool is positioned in front of said ends when clamping the clip on the conduit.

5 2. In a tool for installing a band-like conduit-embracing and supporting clip having a pair of opposed ends adapted to be forced together to clamp the clip on a conduit and position said ends for application thereto of means for securing them together, a pair of opposed arms spaced apart and adapted to be positioned opposite corresponding edges of said ends of the clip, opposed inwardly turned ends on said arms forming a pair of jaws for engaging the outer face of one of the ends of said clip, an operating lever, means for pivotally connecting the ends of said arms opposite to the jaws to said lever to provide a fulcrum for the lever, a plate-like link having one of its ends pivoted on the lever between one end of the lever and the fulcrum therefore, said link having its other end presenting an edge transversely of and between said arms as a jaw to engage the outer face of the other of said ends of the clip; and tongues on said link bent around said arms and slidably holding the jaw end of the link on said arms, said link having an opening therein adjacent its jaw end through which opening a bolt or screw may be inserted and removed.

15 3. In a tool for installing a band-like conduit 30 embracing and supporting clip having a pair of opposed ends adapted to be forced together to clamp the clip on a conduit and position said ends for application thereto of means for securing them together, a pair of opposed arms spaced apart and adapted to be positioned opposite corresponding edges of said ends of the clip, jaw 35 means extending between said arms at certain corresponding ends thereof for engaging the outer face of one of the ends of the clip, an operating 40 lever, means pivotally connecting the other ends of said arms to said lever to afford a fulcrum therefor, and an elongated member including a jaw portion which is slidably supported over said arms for movement into and out of engagement 45 with the outer face of the other of the ends of said clip, said member having through it an opening adjacent to its said jaw portion to permit access therethrough to the ends of the clip when the tool is positioned in front of said ends when 50 clamping the clip on a conduit.

EUGENE M. MOREHOUSE.
